UNITED STATES PATENT OFFICE.

SAMUEL TRIPPI, OF BUFFALO, NEW YORK.

DESIGN FOR A GOBLET OR SIMILAR ARTICLE.

Application filed March 12, 1923. Serial No. 5,438. Term of patent 7 years.

To all whom it may concern:

Be it known that I, SAMUEL TRIPPI, a citizen of the United States, residing at Buffalo, in the county of Erie and State of New York, have invented a new, original, and ornamental Design for Goblets or Similar Articles, of which the following is a specification, reference being had to the accompanying drawing, forming part thereof.

In the drawing:—

Figs. 1 and 2 are side views of a glass container in the form of a goblet, the views being taken at right angles to each other.

I claim:

The ornamental design for a goblet or similar article, as shown.

SAMUEL TRIPPI.
